UNITED STATES PATENT OFFICE.

WALTER R. TRIGG, OF ROCKFORD, ILLINOIS.

DESIGN FOR A MONUMENT.

46,072.

Specification for Design.

Patented July 7, 1914.

Application filed May 8, 1914. Serial No. 837,834. Term of patent 3½ years.

To all whom it may concern:

Be it known that I, WALTER R. TRIGG, a citizen of the United States, residing at Rockford, in the county of Winnebago and State of Illinois, have invented a new, original, and ornamental Design for Monuments, of which the following is a specification, reference being had to the accompanying drawings, forming part thereof.

Figure 1 is a front elevational view of a

monument, showing my new design; and Fig. 2 is a side elevational view of Fig. 1.

I claim:

The ornamental design for a monument, as shown.

WALTER R. TRIGG.
